CLAIMThe ornamental design for a two-piece welding helmet, as
shown and described.**DESCRIPTION**

FIG. 1 is perspective view of a first embodiment of a
two-piece welding helmet showing my new design it being
understood that the opposite side is a mirror image thereof;
FIG. 2 is a perspective view of a second embodiment of a
two-piece welding helmet it being understood that the
opposite side is a mirror image thereof; and,
FIG. 3 is a perspective view of third embodiment of a
two-piece welding helmet it being understood that the
opposite side is a mirror image thereof.

The surfaces or portions of the bottom and rear views of the
two-piece welding helmet not shown in the drawing or
described in the specification form no part of the claimed
design.
